(57) **CLAIM**

The ornamental design for a mounted temperature controller, as shown and described.

DESCRIPTION

FIG. 1 is a rear perspective view illustrating a mounted temperature controller;

FIG. 2 is a front perspective view of the mounted temperature controller;

FIG. 3 is a top plan view of the mounted temperature controller;

FIG. 4 is a bottom plan view of the mounted temperature controller;

FIG. 5 is a rear elevation view of the mounted temperature controller;

FIG. 6 is a front elevation view of the mounted temperature controller;

FIG. 7 is a left side elevation view of the mounted temperature controller;

FIG. 8 is a right side elevation view of the mounted temperature controller;

FIG. 9 is a rear perspective view illustrating another mounted temperature controller;

FIG. 10 is a front perspective view of the mounted temperature controller of FIG. 9;

FIG. 11 is a top plan view of the mounted temperature controller of FIG. 9;

FIG. 12 is a bottom plan view of the mounted temperature controller of FIG. 9;

FIG. 13 is a rear elevation view of the mounted temperature controller of FIG. 9;

FIG. 14 is a front elevation view of the mounted temperature controller of FIG. 9;

FIG. 15 is a left side elevation view of the mounted temperature controller of FIG. 9;

FIG. 16 is a right side elevation view of the mounted temperature controller of FIG. 9;

FIG. 17 is a rear perspective view illustrating another mounted temperature controller;

FIG. 18 is a front perspective view of the mounted temperature controller of FIG. 17;

FIG. 19 is a top plan view of the mounted temperature controller of FIG. 17;

FIG. 20 is a bottom plan view of the mounted temperature controller of FIG. 17;

FIG. 21 is a rear elevation view of the mounted temperature controller of FIG. 17;

(Continued)

FIG. 22 is a front elevation view of the mounted temperature controller of FIG. 17;
FIG. 23 is a left side elevation view of the mounted temperature controller of FIG. 17; and,
FIG. 24 is a right side elevation view of the mounted temperature controller of FIG. 17.
The broken lines in the drawings depict environment that forms no part of the claimed design.
